Fig. 1 is a side elevational view of a lawn sprinkler or similar article showing my new design with a portion of the spike shown broken away in part to indicate indeterminate length;

Fig. 2 is a front elevational view thereof with a portion of the spike omitted for convenience of illustration only;

Fig. 3 is a perspective view thereof as shown in Fig. 2; and

Fig. 4 is a vertical sectional view through the discharge end of the sprinkler.

The right side of Fig. 1 is substantially plain and has a centrally tapped hole which is conventional for receiving a threaded hose connection.

This is a continuation-in-part of my prior application Serial Number D. 46,517, filed June 7, 1957.

I claim:
